DESIGN FOR A LUSTER OR SIMILAR ARTICLE

George Sakier, New York, N. Y., assignor to Fostoria Glass Company, Moundsville, W. Va., a corporation of West Virginia

Application November 10, 1934, Serial No. 53,960

Term of patent 14 years

To all whom it may concern:

Be it known that I, George Sakier, a citizen of the United States of America, and resident of New York, county of New York, and State of New York, have invented a new, original, and ornamental Design for a Luster or Similar Article, of which the following is a specification, reference being had to the accompanying drawing, in which—

I claim—

The ornamental design for a luster or similar article, substantially as shown and described.

GEORGE SAKIER.
